UNITED STATES PATENT OFFICE.

LEWIS M. TEBBEL, OF SPOKANE, WASHINGTON.

SELF-FILLING FOUNTAIN PEN.

Application filed February 2, 1925. Serial No. 6,333.

To all whom it may concern:

Be it known that I, LEWIS M. TEBBEL, a citizen of the United States, residing at Spokane, in the county of Spokane and 5 State of Washington, have invented new and useful Improvements in Self-Filling Fountain Pens, of which the following is a specification.

This invention relates to improvements in 10 self filling fountain pens and has to do with the closed barrel type wherein the collapsing means is actuated from the butt or rear end of the pen barrel.

A feature of special importance resides in 15 the provision of a very materially increased leverage, over pens of this general type now known to me thereby not only rendering the collapsing movement easier but surer and more definite.

Another feature consists in relieving the 20 ink sack of any "pull" or "drag" as a result of collapsing movement of the sack bar, and also freeing the sack bar from the necessity of sliding along the sack as the latter is 25 being collapsed.

My invention also includes a novel form 30 of lever which is constructed and arranged to not only afford an increased leverage, but which is tiltably or pivotally mounted in such a manner as to impart an endwise movement to the sack bar toward the pen end of the barrel so as to avoid slippage of the bar along the sack as the latter is being deflated.

35 My invention includes many other features which will be more fully described in connection with the accompanying drawing and which will be more particularly pointed out in and by the appended claims.

40 In the drawing:—

Fig. 1, is a view partly in section and partly in elevation, showing the most improved form of my invention with the sack inflated.

45 Fig. 2, is a sectional view showing the manner of deflating the ink sack.

Fig. 3, is a plan view of the deflating or collapsing mechanism detached from the pen barrel.

50 Fig. 4, is a view in side elevation of said mechanism.

Fig. 5, is a detail plan view of a portion 55 of the lever showing the same provided with pivot trunnions for connection with the sack deflating bar.

Fig. 6, is a sectional view on line 6—6 of Fig. 1.

Fig. 7, is a sectional view on line 7—7 of Fig. 3.

Like characters of reference designate 60 similar parts throughout the different figures of the drawing.

As shown, 1 designates the usual pen barrel in which the usual pen section 2, telescopes. The pen section 2, carries the feed 65 bar and pen, and to which the usual ink sack 3, is secured. In this type of pen, the pen section 2, is frictionally detachable with the barrel 1, and can be removed or attached thereto, and when being assembled, the ink 70 sack 3, is inserted into the barrel 1, in the usual manner. It will be noted that in this construction, the ink sack is of such diameter, when inflated, that it substantially fills the cross sectional interior of the barrel 1. The rear or butt end of the barrel 1 is reduced at 4, forming a shoulder 5, and is exteriorly threaded so that a cap 6, may be 75 screwed onto or off from the barrel.

I will next refer to the sack collapsing 80 mechanism which forms the invention herein claimed.

This improved mechanism includes a lever which I will first describe in detail and which, as shown, is formed of a single strip of metal. One end of said lever, as indicated at 7, constitutes the bar actuating section which is operatively associated with a sack 85 deflating bar 8, in a manner to be later described. The remaining end of said lever forms a finger-grip section 9, and extends endwise outwardly through the barrel 1, as clearly shown in Figs. 1 and 2. An intermediate portion of the lever is looped to 90 form a pivot section and one limb 10, of said loop, and which is the longer limb, forms a continuation of section 7 and is shown bent at substantially right angles thereto. The remaining limb 11, which is the shorter limb, forms a continuation of section 9, which latter is bent at substantially right angles thereto. These limbs 10 and 11, are disposed in flat abutting relation and the resulting structure 95 serves very materially to strengthen the pivot section of the lever.

The right 12, of the looped pivot section, is 100 adapted to coact with a pivot pin 13, which is inserted through the barrel 1, as clearly shown in Figs. 1 and 6. The extreme end 14, of section 7, is provided with pivot trunnions 105 for connection with the sack deflating bar. 110

nions 15, projecting laterally therefrom, whereto the bar 8, is pivotally connected with section 7.

Reference will next be made to bar 8.

5 Said bar 8 is of a length substantially co-extensive with the length of the deflatable portion of the sack 3, as shown. Near its central portion, said bar has downwardly extending flanges 16 which taper towards 10 and merge into the ends 17 and 18, of said bar 8, so that the end portions will only be about the thickness of the metal of which the bar is formed. The flanges 16, are provided with pivot holes into which the pivot 15 trunnions 15, are suitably fitted, as shown. This pivotal connection of section 7 and bar 8 is sufficiently nearer end 18, of said bar, than end 17, thereof, so that the lever will cause end 18 to collapse the rear end of sack 20 3 first, and gradually collapse the remainder thereof. This is clearly an advantage in eliminating air pockets and the consequent defective deflation resulting therefrom.

The bar 8, is not flat on its upper face, but 25 the pen end 17, is downwardly arched from the center of the bar so that when the rear portion of bar 8, lies flat on section 7, the forward or pen end 17 will be in close relation to the barrel 1, as shown in Fig. 4, 30 thereby avoiding any obstructing interference when inserting the sack 3, into the barrel.

When a sack deflating bar is pivotally connected with a lever that tilts the bar into a 35 sack deflating position, there has heretofore been encountered an objectionable "pull" or "drag" by reason of the fact that the bar was slightly drawn rearwardly, or away from the pen end, when being swung into a 40 deflating position. This defective action was due to the fact that the sack was moved laterally of the barrel, the tendency being to tighten or draw taut that portion of the sack indicated at 19. Thus, it will be clear 45 that if in deflating the sack the bar 8, were drawn rearwardly, there would have to be some sliding movement of the bar with respect to the sack. This sliding movement, by reason of the added friction, resulted in 50 the mechanism not only working under greater resistance, but also caused undue wear on the sack at just that area thereof where the wear is most objectionable and where the sacks almost always first wear out.

55 It is one of the primary objects of this invention to prevent such defective action of the bar 8, and I will next describe the manner and means whereby this is accomplished.

60 It will be noted, in Fig. 1, that bar 8 and section 7, are on one diametrical side of the longitudinal axis $a-a$, of the pen barrel 1. Now the pivot section extends across the bore of the barrel 1, and the pivot pin 13 is on that side of line $a-a$ diametrically opposite the side on which bar 8 and section 7

are disposed. This disposition of the tilting or pivotal axis of the lever is such that viewing Fig. 2, it will be clear that pin 13, is above bar 8, even when said bar is in a full deflating position. Now by reason of this 70 construction, it will be clear that instead of pulling bar 8 away from the pen end of the barrel 1, bar 8 is actually shifted slightly toward the pen end, while it is being swung into a deflating position. This effectively 75 relieves portion 19, of sack 3, from any strain. In fact, the shifting movement of bar 8, forwardly, is sufficient to entirely neutralize any tautness in the sack 3 and permit portion 19 to be as free from tension 80 as any other part of the sack. In Fig. 2, b designates the position of trunnion 15, when the bar 8, is in a non-deflating position, and the curved line c is the arc which the pivotal connection described about pivot 13, in moving from a non-deflating to a deflating position. The distance d is the extent of shift 85 of the bar 8, toward the pen end of barrel 1, which in practice, in a large size pen, amounts to approximately three one hundredths of an inch. It will be readily understood that if pin 13, were disposed below line $a-a$, viewing Fig. 2, there would be an endwise movement of bar 8, to the right, instead of to the left of said figure. 90

Irrespective of whether the pivot section 95 extends completely across the bore of the barrel 1, it will be clear that any extension of said section from the bend 20, will serve to increase the leverage of the deflating lever, and obviously, it is important to make 100 this increase to the maximum, as shown. With this greatly increased leverage, in addition to the fact that movement of bar 8 toward the pen end greatly decreases the resistance in operating the mechanism, it will be clear that I obtain not only effective action, but I obtain it with a minimum of exertion and a maximum of freedom. 105

It will now be clear that the sack deflating bar and lever, together with the pivotal mounting of the latter, constitutes sack collapsing mechanism adapted to be operated from the butt end of the barrel and serving 110 to first impart a preliminary endwise collapsing thrust on the sack toward the pen end of the barrel, to neutralize "draw" on the sack, said mechanism imparting a final collapsing thrust toward one wall of the 115 barrel.

120 In large size pens, the space required for movement of the finger-grip section 9, is ample, as shown. However, in the smaller sizes, this space is very limited. Therefore, to obtain the required movement of section 9, it is desirable to so shorten limb 11, that section 9, in the normal position shown in Fig. 1, will lie very close to the upper perimeter of extension 4, so as to have plenty of 125 room to be depressed without coming in contact with the upper edge of extension 4. 130

tact with the lower perimeter of extension 4.

It is a feature of my invention to make the lever and the collapsible bar of rigid instead of resilient material, and it will be noted that I do not employ a spring or other means for returning or maintaining these parts in the normal position shown in Fig. 1. From the foregoing, the advantage of having a sack that substantially fills the bore of the barrel will now be understood as inflation of the sack serves to restore and maintain the lever and bar in the position shown in Fig. 1.

It is believed that the advantages of my invention will be fully understood from the foregoing description, and while I have herein shown one specific form of my invention, I do not wish to be limited thereto except for such limitations as the claims may import.

I claim:—

1. In a self filling fountain pen, a barrel, a collapsible ink sack in said barrel, a rigid sack collapsing bar in said barrel alongside said sack, a rigid lever having one end forming a bar actuating section disposed between said bar and barrel on one side of the longitudinal axis of said barrel, an intermediate portion of said lever being looped and forming a pivotal section extending across the longitudinal axis of said barrel to a point opposite the location of said actuating section and being pivoted to said barrel at the bight of said loop, and the remaining end of said lever extending endwise and outwardly through said barrel and forming a finger grip section whereby said lever may be manually operated.

2. In a self filling fountain pen, a barrel, a collapsible ink sack in said barrel, a sack collapsing bar in said barrel alongside said sack, a lever having one end forming a bar actuating section and pivoted to said bar, the remaining end of said lever extending endwise through said barrel and forming a finger-grip section, and means pivoting an intermediate portion of said lever to said barrel at a point opposite the location of said bar and actuating section, whereby collapsing actuation of said lever will shift said bar endwise toward the pen end of said barrel to neutralize "draw" on said sack.

3. In a self filling fountain pen, a barrel, a collapsible ink sack in said barrel, a sack collapsing bar between said sack and barrel, a tiltable lever in said barrel having one end forming a bar actuating section and pivoted to said bar, the remaining end of said lever extending endwise outwardly through said barrel and forming a finger-grip section, and causing said bar to shift endwise toward the pen end while said bar is collapsing said sack.

4. In a self filling fountain pen, a barrel, a collapsible ink sack in said barrel, and sack collapsing mechanism in said barrel and operable from the butt end thereof for imparting a preliminary endwise collapsing thrust on said sack toward the pen end to neutralize "draw" on the sack and a final collapsing thrust toward one wall of the barrel.

In testimony that I claim the foregoing as my own, I hereby affix my signature.

LEWIS M. TEBBEL.
